CLAIM

We claim the ornamental design for a micro-module data center, as shown and described.

DESCRIPTION

FIG. 1 is a front, left-side, and top perspective view of a micro-module data center showing our new design; FIG. 2 is a rear, right-side, and bottom perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is an enlarged view of the circled portion 9 of FIG. 1; FIG. 10 is an enlarged view of the circled portion 10 of FIG. 1;

FIG. 11 is an enlarged view of the circled portion 11 of FIG. 1; and,

FIG. 12 is an enlarged view of the circled portion 12 of FIG. 2.

The broken lines depict portions of the micro-module data center in which the design is embodied that form no part of the claimed design.

The dot-dash lines depict the boundaries of the enlarged views and also form no part of the claimed design.
